UNITED STATES PATENT OFFICE.

WILLIAM BRECKNELL, OF WEST HARTLEPOOL, ENGLAND, ASSIGNOR TO
GEORGE CHATTAWAY, OF SAME PLACE.

MEANS FOR RAISING OR LOWERING DOOR OR LIKE CURTAINS OR SCREENS.

SPECIFICATION forming part of Letters Patent No. 615,605, dated December 6, 1898.

Application filed September 17, 1898. Serial No. 691,225. (No model.)

To all whom it may concern:

Be it known that I, WILLIAM BRECKNELL, a subject of the Queen of Great Britain and Ireland, residing at 4 Averill Terrace, Middleton road, West Hartlepool, in the county of Durham, England, have invented certain new and useful Improved Means for Raising or Lowering Door or Like Curtains or Screens, (for which I have applied for a patent in Great

10 Britain under No. 25,572, dated November 4, 1897,) of which the following is a specification.

15 My invention relates to improved means for raising and lowering curtains or screens, and relates to that kind which are suspended on doors or the like and so adapted as to cover same and lie upon the floor or analogous part to effectually exclude drafts. According to the usual practice the bottom or lower edge of the curtain or screen becomes worn and 20 damaged in opening and shutting the door, such movements, in addition, being often impeded by the curtain, and though means have been devised to obviate these defects they have not attained to the desired requirements 25 by reason of their clumsy and inconvenient character; and my object is to provide simple and handy means whereby the above disadvantages are overcome in a neat and efficient manner.

30 My invention consists in the combination of a resilient piece or member or spring, curtain-rod-supporting levers, a striking or operating lever, arm or contact-pieces, a stop or projections, and certain auxiliary parts so arranged 35 that on opening the door the curtain is automatically raised from the floor or drawn up a predetermined distance to prevent damage and impediment and on closing the curtain is automatically returned to its original position to exclude drafts.

40 In order that my invention may be fully understood, I will explain it in reference to the accompanying drawings, which illustrate it as applied to a door.

45 Figure 1 is a general front elevation showing the position of the improved means when the door is closed, and Fig. 2 is an end elevation of same. Fig. 3 is a similar view to Fig. 1, representing the position assumed when 50 the door is opened. Fig. 4 is a sectional plan

of the arrangement of the aforesaid resilient piece or member, and Figs. 5 and 6 are respectively a vertical section and an end elevation of details of same. Fig. 7 is a longitudinal section of a detail in the construction of the 55 curtain-rod. The four latter figures are drawn to a larger scale than the first three for the sake of clearness, and for the same reason the curtain is omitted from Fig. 1.

A is a tube supported and revoluble in 60 brackets B B' B², attached to the door C. The function of this tube is to inclose a resilient piece or member in the form of a rectangular or other transverse sectioned strip or bar D, capable of being twisted or put in a 65 torsional condition, for which purpose it is rigidly connected to the tube A at the right-hand end and at the other to the bracket B. These fixtures are conveniently arranged, as shown in Figs. 4, 5, and 6, wherefrom it will 70 be seen that I make the bar D with terminal square portions d d', the former being fitted into a corresponding hole in a thimble or holder E, placed inside the tube A and secured thereto by a pin e, while the portion d' 75 is inserted in a sleeve or carrier F, arranged partly within the tube A and provided outside of same with an intermediate ring or flange f, whereby it is united to the bracket B by a screw or pin G, passed through one of a graded 80 series of holes f' f' in the flange into a hole in the boss of the bracket. The sleeve F is so fitted within the tube A that it may be revolved independently of the other, and for turning the former I form it beyond the 85 flange f with a square part f² to receive a suitable operating-tool. The tube A is revolved, as hereinafter explained. Supposing the screw G is displaced, then the sleeve F is 90 free to be turned within the tube A by a spanner, for example, applied at the part f², and when it is turned and the tube A suitably held rigid the strip D, due to its immovability at one end consequent on its connection to the tube A and its fixture in the sleeve 95 F at the other, is forced into a condition opposing its normal tendency, the degree of which is determined by the amount of curtain lift desired, and maintained on reuniting the flange f to the bracket B by the screw G. The 100

object of the holes $f' f''$ is to admit of various adjustments in this respect. For appearance an ornamental cap f^3 is shown fitted over the flange f and square part f'' .

5 H is a rod from which the curtain is suspended in the usual way. It is carried by brackets or levers J J' J'', fixed by pins or otherwise to it and to the tube A as well. Therefore they are integrally united, any 10 movement imparted to the tube being communicated to the rod, and consequently the curtain also. The lever J' has formed on or fixed to it an arm or contact-piece K, adapted to coact with a projection or stop L, attached 15 to the wall M (or it might be the door-frame) in such manner that when they are forced into contact the tube A, by reason of its connection with the arm or prolongation K through the lever J', is revolved in the brackets B B' B'' against the force exerted by the bar D, which when the said contact is broken effects its revolution the other way. The 20 amount of these revolutions may be limited, as shown in Fig. 1, by providing on the tube 25 A a pin a to work in a bifurcation b of the bracket B'.

In the foregoing I have described the construction of my invention. Now I will explain its working, which is as follows: Assuming the curtain I is raised completely off the floor, then the parts will be in the positions illustrated by Fig. 3, and on closing the door C the arm K strikes and is pressed backward by the stop L, which has the effect of 30 turning the tube A in its brackets B B' B'', whereby the rod H is depressed and the curtain lowered, this state being maintained by the continued contact of the arm K and stop L on the complete closure of the door, as shown 35 in Figs. 1 and 2. Synchronously with the movement of the tube A, rod H, and curtain I the strip D is twisted or subjected to torsion, since its end d is fastened to the tube and turns therewith, while the end d' is immovable, due 40 to its connection at the bracket B. Thus it will be understood the door C is closed and the curtain I lowered in opposition to the resiliency of the strip D. On opening the door the arm K leaves the stop L. Therefore the 45 strip D is permitted to resume its original condition, and under this reaction the tube A is rotated in the reverse direction to that before referred to, the rod H is raised, and the curtain I lifted the predetermined amount, as illustrated in Fig. 3. In this way the curtain 50 is positively actuated, the lifting resulting simultaneously with the opening of the door and lowering on closing it, all dragging being abolished and the life of the curtain 55 thereby prolonged.

In arrangements of this kind usually the curtain-rod projects at each end beyond the door to enable the curtain to completely cover same. Hence in the general situation of doors, 60 as indicated in Figs. 1, 2, and 3, a flexible joint at the hinge side is necessary in the rod

to prevent it fouling the wall or its equivalent on opening the door and at the same time maintain the curtain in the required position, so that when the door is closed the curtain 70 will require no readjusting. In constructing such a joint I make the rod H wholly tubular or only at the end adjacent to the door-hinges, whereat I divide it transversely, whence two parts h h' result, into each of which I fit a 75 plug N, one being furnished with a double eye and the other with a single eye, which are fitted together and united by a pin n to form a hinge. In the outer end of the part h' I insert another plug P, provided with a roller 80 p, adapted to run on a plate Q, as shown in Figs. 1 and 3, fixed on the wall M to preserve it. The roller and plate can, however, be dispensed with, if desired; but I prefer to use them. As clearly shown in Fig. 7, a hole is 85 made in each plug N, through which passes a cord or chain R, having one end fastened by knotting or otherwise at the inner end of the plug N within the part h of the rod H and its other end joined to a spring S, in turn 90 united to the plug P. Thus on opening the door C the rod H instantly rises, as before described, and comes in line with the plate Q, and as the door is opened wider the part h' comes in contact with the said plate, thereby 95 causing the rod to bend at the juncture therein against the pressure of the spring S, as represented in Fig. 3, the part h' running on the plate Q. On closing the door the rod H resumes its initial position, as shown in Figs. 1 100 and 7, under the action of the spring S. Instead of this joint I may of course adopt any of the known joints that may be suitable.

As will be evident, the construction of my improved means is neat and compact, there 105 being no unsightly levers, cords, &c., exposed to view when the curtain is drawn or removed, as in some of the present arrangements, and the parts are made of any appropriate material or materials having the visible surfaces 110 polished or otherwise adapted to render the appearance pleasing.

Though I have described my invention in regard to door-curtains, for which it is specially intended, still it may be applied to analogous curtains or screens and the details may be varied according to circumstances. For example, instead of a simple resilient bar a compound one may be employed, and there may be two or more stops or projections on the 115 wall or door-framing for coacting with a similar number of striking arms or prolongations in connection with the curtain-rod.

Having now described my invention, what I claim as new, and desire to secure by Letters 120 Patent, is—

1. In combination, in a curtain-raisng mechanism, the curtain-rod, means connected therewith for raising the same, a striking arm or lever connected with said means to control it in its operation and a stop on the wall for operating the striking-arm, said striking-arm 130

and curtain-rod being carried by the door, substantially as described.

2. In combination with the door, a curtain-rod, brackets supporting the same, a resilient bar or strip connected with the brackets to raise the said curtain-rod and extending longitudinally of the curtain-rod, and means for resisting the lifting tendency of the strip when the door is closed, substantially as described.

3. In combination, the door, the curtain-rod, the brackets carrying the same, the resilient rod D connected to the brackets, the cover A for the rod, the striking-lever connected with the strip and the stop on the wall, substantially as described.

4. A curtain-rod having a flexible end joint

combined with a contact-plate on the wall and means for supporting the said rod with its flexible end joint upon the door so that the main part and the end joint will both move with the door.

5. A curtain-rod having a flexible end joint and a spring for holding the jointed part in line with the main portion, substantially as described, said spring being within the curtain-rod and exercising its tension longitudinally thereof.

In witness whereof I have hereunto set my hand in presence of two witnesses.

WILLIAM BRECKNELL.
